(57) **CLAIM**

The ornamental design for a “packaging container,” as shown and described.

DESCRIPTION

FIG. 1 is a perspective view of a packaging container, showing our new design in open condition;
 FIG. 2 is a front elevational view;
 FIG. 3 is a rear elevational view;
 FIG. 4 is a first side elevational view;
 FIG. 5 is a second side elevational view;
 FIG. 6 is a top plan view; and,
 FIG. 7 is a bottom plan view.
